UNITED STATES PATENT OFFICE.

AUGUST ZÖBELEIN, OF NUERMBERG, GERMANY.

CONVEYING DEVICE.

Application filed April 7, 1926, Serial No. 100,470, and in Germany May 11, 1925.

My invention relates broadly to a device for conveying ashes, slag, sand or the like with the aid of water under pressure and more particularly to a construction of apparatus for facilitating the transfer of agglomerate through a pipe line system.

The characteristic feature of the invention resides in the transportation of masses from several different places at which agglomerate material is deposited direct to a storage place by means of a single substantially straight guiding pipe thereby avoiding the usual distributing and collecting pipings with undesirable bends, which are subjected to heavy wearing and cause a loss of pressure.

Not only does the single pipe convey the mixture of agglomerate material with the water as a suspension fluid from any given hopper to the storage place but this single pipe also conveys the water under pressure from the source of power to the hopper being emptied.

To accomplish the above I provide individual ejector nozzles at the several depositing places in the pipe line. The insertion of these nozzles is made by an arrangement of an expansion mechanism capable of loosening the pipe line flanges between which lies a slide carrying the ejector nozzle. The flanges are brought together again for tightly locking the ejector nozzle in position.

In order that the invention may be clearly understood, I shall proceed to describe the same with reference to the example of a preferred construction shown in the accompanying drawing, wherein:

Fig. 1 is a side elevation in vertical cross section taken on line 1—1 of Figure 3;

Fig. 2 is an end elevation taken in cross section along the line 2—2 of Fig. 1;

Fig. 3 is a plan view, being a horizontal cross section taken along line 3—3 of Fig. 1; and

Fig. 4 is a sketch in outline showing a side elevation of a plurality of the units of Fig. 1 assembled in place in an agglomerate disposal system comprising the single pipe above mentioned.

Referring to the drawings, the ejector slide 10 comprises two portions and in one portion there is located the nozzle 1, the agglomerate intake 2, and the diffusion chamber 3. The diffusion chamber is necessary when the agglomerate is to be conveyed to

great heights and for long distances. The other portion of the ejector slide 10 consists of the open passage 4. The movement for shifting the slide so that either portion of the slide is in operative position can be effected for example by means of a spindle 9, which as shown in Fig. 2 is screw threaded and held against rotation. The handwheel engaging these threads is held against end movement by a support not shown, therefore the rotation of the handwheel will move the shaft 9 endways and, along with it, the slide device 10.

With the aid of the expansion mechanism 6, which is screw actuated, the flange 5 is loosened when the slide device 10 is to be moved and tightened again after the slide has been shifted. Reference characters 7 and 8 indicate elastic gaskets for insuring a tight joint at opposite ends of the slide when the expansion mechanism is tightened.

In Fig. 4 of the drawing I have designated with reference characters C¹, C² and C³ the several depositing places, such as the ash-hoppers of a battery of boilers. A conducting pipe for water under pressure is designated as 17 the inlet of which is P; E¹, E² and E³ are the ejector slide-devices, and D is the outlet end of the conveying pipe located adjacent to the storage place.

The slide E² may be readily moved into the operative position by means of the hand screw or spindle 9, the slide moving in guides provided by the interconnecting bars 15, which bars interconnect the end plates 12 and 14. The end plate 12 has an aperture to conform with the cross-section of the pipe line 17. The end plate 12 and flange 5 are spread or expanded by actuation of the screw mechanism 6 for loosening the gaskets 7 and 8 from the ends of the slide, enabling the slide to be shifted sidewise. After shifting, by reversing the movement of the screw mechanism 6, the end plate 12 and flange 5 are brought together for gripping the ends of the slide in the newly selected position. A crank, not shown, is attached to the squared end of the spindle 16 for driving worm 11 and rotating screw mechanism 6 for spreading or expanding the end plate 12 and flange 5. There is sufficient elasticity inherent in the pipe line to permit slight longitudinal contraction and expansion for enabling the slide to be shifted in position and also a tight joint is insured between the

ends of the slide and the abutting ends of the pipe line when the gaskets are brought back to their normal condition.

More in detail, when a hand crank is applied to the squared end of the shaft 16 to rotate worm 11, a slow turning of worm gear or worm wheel 18 results. Worm gear 18 is keyed to sleeve 6 and this sleeve bears strong threads 19. The end plate 14 has a much larger opening than that in end plate 12 and this opening is internally threaded to engage threads 19. The opening within the sleeve 6 is about the size of the opening in plate 12 and fits around a very short piece of pipe 20, loose enough to rotate freely. This piece of pipe 20 has rigidly attached thereto a flange 21 at one end and a flange 5 at the other end. End plate 14 is kept from having axial or longitudinal motion relative to end plate 12 by means of the four heavy interconnecting bars 15. The rotation of sleeve 6 with threads 19 inside of stationary end plate 14 will produce axial motion in sleeve 6 toward or from end plate 12 and this end motion of sleeve 6 will be transmitted by means of flanges 21 and 5 and short pipe 20 so as to move flange 5 toward or away from end plate 12, thus tightening or loosening the slide device 10 held between 12 and 5. Worm wheel 18 has side motion with respect to worm 11 but the amount of such motion is so slight that the teeth of wheel 18 would never come anywhere near escaping from the spiral on worm 11. Also, the end motion imparted to pipe 17 as a result of its being bolted to flange 21 is so slight as to cause no more difficulty than expansion and contraction due to heat and cold.

The diffusion chamber 3 narrows the passageway in front of the nozzle so that the particles of agglomerate can be actually struck by the jet even though the jet may be quite narrow at this point. This, of course, aids in the mixing and hence in the formation of a good suspension. The liner or diffusion chamber 3 also protects the main casting forming the ejector slide 10 against undue wear at a point where the agitation of the agglomerate particles is at a maximum.

The operation of the conveying device is as follows:

Looking at Fig. 4, and assuming that the ashes are to be removed from hopper C^2 , the positioning of the various slide devices would be as indicated below. The slide E^1 under hopper C^1 would be moved to bring tubular portion 4 in exact alignment with the pipe 17. Thus, the suspension of agglomerate in water coming from C^2-E^2 could pass underneath C^1 without hindrance. The slide E^1 under the plurality of hoppers C^1 would likewise be positioned with their openings 4 in alignment with the pipe 17 so

that the pure water coming from the pump or source of power not shown would meet no obstruction as it passes under the hoppers C^1 on its way to the hopper C^2 . The slide device E^2 under the hopper C^2 is positioned just the opposite to that of all the other slides, so that the pipe 17 is deliberately obstructed by the nozzle 1 so that the entire volume of water entering at the end P is forced through the opening in said nozzle

1. The more or less gentle flow in pipe 17 is forced from the nozzle with great velocity thereby tearing apart bit by bit the mass of agglomerate which descends through the opening or agglomerate inlet 2 which is carried by the nozzle side of the slide device. A thorough mixing of the agglomerate with the water ensues so that a suspension is obtained that will readily flow through outlet end D without clogging.

This use of the conveyor pipe to transmit the water pressure to the nozzle adjacent that particular hopper being emptied has the advantage of avoiding a multiplicity of pipes as is the case where piping separate from the conveyor pipe is used to transmit the power transmitting pressure fluid to nozzles adjacent the agglomerate intakes.

Any attempt to use a single unobstructed pipe without the insertion of a jet at the point where agglomerate is being drawn in may result in a complete failure to "draw in" or may result in clogging.

It should be especially noted that the substitution of what is in effect a short length of pipe, namely, tube 4, for the nozzle and agglomerate inlet results in the restoration of the pipe to normal contour at points opposite hoppers not being emptied and results in a complete avoidance of pockets and eddy currents as would be the case if a common gate valve were used in the constricted neck at the bottom of the hopper. Also, the use of the cross sliding ejector piece 10, enables the nozzle 1 to be completely removed from the pipe 17 without the presence of side pockets either during its use in or absence from the pipe.

The invention is not limited in detail to the single modification described above for illustrative purposes, but numerous variations can be made and such variations are intended to be limited only by the scope of the claims.

I claim as my invention:

1. In a conveyor system, a pipe line subdivided into sections and adapted to bear a fluid current, means for longitudinally spreading said pipe line sections, a member positioned between said sections and slidably during said spreading, a hopper located adjacent the member, said slidable member comprising a pair of portions each adapted to register individually with said pipe line, one of said portions forming a mere con-

tinuation of said pipe, and means in another portion of said slidable member for admitting and subjecting material delivered by said hopper to pressure from said fluid current for the conveyance of said material through said pipe line.

2. In a system for conveying agglomerate, sections of pipe line for bearing a current of fluid, a frame structure positioned intermediate the sections and capable of moving said sections further apart, a slide within the frame structure and laterally movable during said increased relation, said slide having portions arranged to be alternately aligned with the axis of said pipe line sections, a hopper for receiving agglomerate, one of said slide portions being arranged to register with said hopper and having a device for forcing material delivered by said hopper through said pipe line sections by means of said current, and the other of said portions being arranged to cut off the connection between said hopper and said sections and provide a free passage for said agglomerate through said pipe line sections.

3. In a conveying system for agglomerate, a pipe line in sections adapted to have a flow of fluid therein, mechanism located between aligned sections of said pipe line for increasing and decreasing the distance between said sections, a structure laterally slid able when said distance is increased and held fluid-tight between said sections when said distance is decreased, said laterally slid able structure having two portions, one

of said portions being arranged to register with a delivery hopper for receiving agglomerate, means in said portion for forcing said flow of fluid through a jet and the other portion of said frame structure being arranged to open the passage through said pipe line while cutting off the delivery of material from said hopper.

4. In a conveying system for agglomerate, a pipe line, a plurality of delivery hoppers for depositing agglomerate in said pipe line at separated points along the length of said pipe line, a shiftable device positioned opposite each of said hoppers and within said pipe line, said shiftable device arranged to be moved to either of two selected positions, means for forcing said agglomerate through said pipe line from a point adjacent a selected one of said hoppers when said device is shifted to a selected position, said pipe line being restored to normal contour for the forcing of said agglomerate therethrough from a point adjacent another of said hoppers when said aforementioned device is shifted to its other position.

5. In a pipe line adapted to convey fluid, a member bearing a nozzle and shiftable to bring the nozzle into alignment with said pipe, said member having a side opening adjacent said nozzle, said member bearing a pipe section that in the unshifted position restores the pipe to an unobstructed condition and restores it to normal contour.

AUGUST ZÖBELEIN.
